UNITED STATES PATENT OFFICE.

GOTTLIEB KLENK, OF DEFIANCE, OHIO, ASSIGNOR TO THE DEFIANCE PRESSED STEEL COMPANY, OF DEFIANCE, OHIO.

STORAGE AND SHIPPING BOX.

1,161,692.

Specification of Letters Patent. Patented Nov. 23, 1915.

Application filed February 12, 1910, Serial No. 543,505. Renewed May 8, 1914. Serial No. 837,313.

To all whom it may concern:

Be it known that I, GOTTLIEB KLENK, a citizen of the United States, residing at Defiance, in the county of Defiance and State of Ohio, have invented certain new and useful Improvements in Storage and Shipping Boxes, of which the following is a specification, reference being had therein to the accompanying drawing.

10 This invention relates to storage and shipping boxes for heavy articles such as bottles containing liquids.

15 The object of the invention is to provide in a covered box capable of being stacked with other similar boxes an improved hinged construction so positioned that the box cover may be held substantially vertical when in its open position.

20 Figure 1 of the drawings is a perspective view of the box as a whole. Fig. 2 is a vertical cross section of the box. Fig. 3 is a bottom plan view of the box. Fig. 4 is a longitudinal section of one box and of the lower part of another box stacked upon it with the 25 cover in a closed position. Fig. 5 is an enlarged vertical section through the hinge device and adjacent parts of one box and the lower edge and bottom parts of another box stacked upon the first box. Fig. 6 is an enlarged fragmentary vertical section through the hinge device and adjacent parts, the 30 cover being shown in open position.

35 The box is formed of six rectangular sections of sheet metal constituting the side walls 1, 1, end walls 2, 2, the bottom 3 and the cover or top 4. The end and side sections are seamed together along their vertical edges. The bottom section is seamed with the lower edges of the side and end sections in flat outwardly extending horizontal flanges 5. The end walls are formed with the hand hold brackets 13, serves to reinforce and stiffen the box against lateral stresses. The cover 4 is formed of a rectangular sheet 40 of metal, the four edges of which are curled to form a bead 14, which incloses the reinforcing wire 15. This cover in all its parts lies, when in closed position, in a horizontal plane below the plane of the bead 10. Thus 45 when the cover is closed, no parts of a box below interfere with the stacking flange 8 of the box above. The cover is hinged to one of the side walls by means of the strap 16. Each of these straps is a piece of sheet metal 50 bent back upon itself at its ends 16^a and bent to form a cylindrical bead 16^b. The ends 16^a

which rest flat against each other are inserted downward through the slots 12^a in flange 12 and are secured to the side wall 2 by means of the rivets 16^c. The bead 16^b is thus brought into position, just above the flange 12 and encircles the reinforcing wire 15 of the cover, the sheet metal of the cover being preferably cut away along the wire 15 to accommodate the hinge beads. As shown in Fig. 6, when the cover is lifted to its open position, it moves slightly beyond the vertical position and is limited in its motion and supported in this upright position by means of the bead 10 which engages the cover along its hinged edge from end to end. By this construction a simple hinging mechanism is provided, which is easy to manufacture, which is inexpensive and strong. It is especially suitable for a box constructed with a flange 12 depressed sufficiently below the top of the box to receive both a beaded cover and a stacking flange of an upper box. The hinge above described, however, is equally applicable to a box, such as is shown in my Reissued Letters Patent No. 12775, wherein the beaded openings 6, which are hemmed and reinforced about their edges to prevent injury to the hands.

45 Four elongated sections 7 of sheet metal are arranged on the under side of the bottom wall 3, along its four outside edges, the outer edges of these sections 7 being interfolded with the bottom wall and the lateral wall in the formation of the horizontal flange 5. The inner edges of these sections are curled to form beads 8, which lie against the bottom wall 3 and which inclose a reinforcing wire 9 which is rectangular in configuration and which form together with the beads a 50 downwardly projecting stacking flange. This stacking flange is adapted to project downward within the upper edges of the box below and to engage laterally such upper edges to prevent horizontal movement of either box with respect to the other.

55 The upper horizontal edges of the lateral walls 1 and 2, of the box, are curled to form the beads 10, which lie vertically over the horizontal flanges 5 and in vertical planes outside of the vertical planes of the body part of the side and end walls. The sheet metal of the side and end walls in forming this bead is carried first outwardly and then up around the reinforcing wire 11, and back in contact with the inner face of the body part of the end and side walls and finally

horizontally inward to form the depressed cover supporting flange 12. This flange 12 is disposed well below the bead 10. The four parts of this flange along the four lateral walls of the box respectively, are united at the corners by means of the brackets 13, the two vertical walls of each of which are riveted to the side and end walls of the box respectively, and the upper horizontal wall 10 of which is riveted to the ends of the adjacent sections of the flange 12. This flange not only supports the cover, but in conjunction with the cover is supported flush with the upper edges of the box. The hinge 15 straps are held securely in position by the rivets 16^c and by the walls of the slots 12^a and will not be torn from position nor distorted under the heavy strains put upon them when the cover is opened and closed. 20 A simple strong hinge strap held securely in position is particularly to be desired to resist the strains put upon it by the cover which is limited in its movement to an upright open position.

25 What I claim is—

1. In a metal packing box, the combination of lateral sheet metal walls formed with beads at their upper edges, a cover arranged to lie between the walls below the horizontal 30 plane of the said beads when in normal position, a support for the cover, hinge devices each secured to the lateral walls and provided with a hinge element to which the edge of the cover is pivotally fastened, the 35 axis of the hinge being disposed below the top edge of the box and adjacent to the lateral wall to which the hinge is secured, whereby the cover, when raised, is supported in an upright position, a bottom structure 40 having a peripheral supporting flange constructed to engage with and rest upon the beads at the upper edges of the walls of a similar box underneath, and a downward extending stacking flange on the bottom positioned inside the supporting flange and arranged to laterally abut the beaded upper edges of the walls of a similar box underneath to prevent lateral displacement of one box with respect to the other.

50 2. In a metal packing box, the combination of lateral sheet metal walls formed with beads at their upper edges, a cover arranged to lie between the walls below the horizontal plane of the said beads when in normal position, the said cover comprising a sheet of metal and a peripheral reinforcing wire around which its edges are wrapped, a support for the cover, hinge devices each comprising a strap secured to one of the lateral 55 walls and bent around the reinforcing wire of the cover to form a pivotal connection, the axis of said connection being disposed below the top edge of the box and adjacent

to the lateral wall to which the hinge strap is secured, whereby the cover, when raised, 65 is supported in an upright position, a bottom structure having a peripheral supporting flange constructed to engage with and rest upon the beads at the upper edges of the walls of a similar box underneath, and a 70 downward extending stacking flange on the bottom positioned inside the supporting flange and arranged to laterally abut the beaded upper edges of the walls of a similar box underneath to prevent lateral displacement of one box with respect to the other. 75

3. In a metal box, the combination of sheet metal lateral walls, a cover, means for supporting the cover in closed position within the lateral walls comprising an inward extending flange secured to the lateral walls of the box in a horizontal plane below the top edge of the box, said flange being slotted longitudinally at points along one wall of the box, and hinge devices for securing the cover to the box, each comprising a pivot element secured to the cover and a strap having a flat part extending downward through one of the slots in the flange and a sleeve 90 part disposed above the flange and embracing the said pivot element, and means for securing the lower end of the strap to the lateral wall, the upper end of the strap being secured in position by the flange slot in 95 which it fits.

4. In a metal box, the combination of lateral walls, a stacking flange secured to the box and extending downward from the bottom plane thereof and adapted to fit within 100 and between the upper edges of a similar box when placed below it, a cover comprising a rectangular sheet of metal and a peripheral reinforcing wire about which the four edges of the cover are wrapped, an inward extending horizontal flange secured to the lateral walls of the box in a horizontal plane below the top horizontal plane of the box and adapted to support the cover at a sufficient distance below the top horizontal plane of the box to receive the stacking flange of a box above, the flange being slotted longitudinally at points along one side of the box, and sheet metal hinge straps having tongues extending downward through the 11 said slots and secured to the side walls of the box below the said flange and each strap further having a cylindrical bead or hinge sleeve above the said flange which encircles the said peripheral cover reinforcing wire. 11

In testimony whereof I affix my signature, in presence of two witnesses.

GOTTLIEB KLENK.
